UNITED STATES PATENT OFFICE.

SAM A. CRAIG, OF EL PASO, TEXAS.

GATE.

1,078,130.

Specification of Letters Patent. Patented Nov. 11, 1913.

Application filed November 23, 1912. Serial No. 733,169.

To all whom it may concern:

Be it known that I, SAM A. CRAIG, a citizen of the United States, residing at El Paso, in the county of El Paso and State of Texas, have invented certain new and useful improvements in Gates, of which the following is a specification, reference being had to the accompanying drawings.

This invention relates to new and useful improvements in gates and more particularly to a gate in which the one hinge point is adapted to be shifted to cause the gate to swing in one direction or the other.

A further object of the invention resides in providing means for shifting the hinge point of the gate from a carriage or wagon on the road-way without leaving the latter.

Still another object of the invention resides in providing a device which is extremely simple and durable in construction, inexpensive to manufacture and one which will be very efficient and useful in operation.

With these and other objects in view, the invention consists in the novel features of construction, combination and arrangement of parts as will be hereinafter referred to and more particularly pointed out in the specification and claims.

In the accompanying drawings forming a part of this application, Figure 1 is a top plan view of the device. Fig. 2 is a side elevation thereof. Fig. 3 is an enlarged vertical section therethrough as seen on line 3-3, Fig. 2. Fig. 4 is a plan view of the shifting plate showing the lower pintle of the gate in section and showing in dotted lines the various positions of the gate as the pintle is moved through the slot in the shifting plate; and Fig. 5 is an enlarged vertical section as seen on line 6-6, Fig. 4.

In describing my invention, I shall refer to the drawings in which similar reference characters designate corresponding parts throughout the several views and in which—

1 indicates a hinge post and 2 a latch post, between which is adapted to be swung the gate 3. This gate is provided with the vertical bar or upright 4, at its hinging end, the upper end of which extends considerably above the upper edge of the gate and is loosely disposed in a bracket or keeper 5, carried on said hinge post 1, and the lower end of said vertical bar or upright 4, is provided with a depending pintle 6, which is adapted to be movably mount-

ed in a stationary object. This stationary object comprises a plate 7, mounted on the ground at the base of the hinge post, having an arcuate groove 8 thereon the bottom surface of which is undulated and receives the lower end of said pintle 6 thereon and in the normal closed position of the gate, this pintle is adapted to be centrally located in the slot.

The latch post 2 has mounted thereon a double set of latch members, the one consisting of a horizontal plate or bar 9 to which is pivoted a pair of spaced apart gravity latch members 10. The gravity latch members have the upper edges thereof beveled toward the outer ends of the same, the space between the inner ends thereof forming a channel 11, and the same are adapted to rest in their lowermost positions upon the studs or pins 12 carried on the plate or bar 9. In the other set of latch members, a plate 13 is provided, above the bar or plate 9, the same being provided with a central cavity 14. A pair of oppositely bent spring latch members 15 are secured to the upper edge of said plate 13, the inner free ends of which depend downwardly into the cavity 14. The outer swinging end of the gate 3 is provided with a pair of outwardly extending lugs 16 which are adapted to cooperate with the latch members above referred to and from the description here given, and the showing made in the drawings, it will be seen that the gate will be locked upon the disposition thereof to its closed position. The action of the latch members as the gate is disposed to its closed position, appears obvious from the construction shown.

Mounted in the ground in alinement with the hinge post 1 and on opposite sides thereof, are the uprights 17 which are of considerable height and have fulcrumed thereon, at the upper ends thereof, the operating levers 18. The one end of each of said levers which extends but a short distance from the fulcrum point has connected thereto a wire, cable or other flexible connection 19 which, after extending through a guiding member 20 on the post 22, between the hinge post and the uprights, is connected to the pintle 6. The opposite end of each of said levers 18 which extend a considerable distance from the fulcrum point, has connected thereto, a flexible connection 21 which depends therefrom to a point over the road-way.

Thus, should a person in a vehicle, on one side of the gate desire to swing said gate so as to pass between the hinge and latch posts, it is only necessary to grasp the connection 21 and pull downwardly thereon, which action will obviously draw the pintle to one end of the groove 8. In being drawn in this groove, the gate will be raised so that the lugs or the like 16 will be raised above their respective latch members and the gate automatically swung to its open position. The guide members 20 are carried on the stop posts 22, which posts will limit the open swinging movement of the gate in either one direction or the other. As the operating means for the gate are on both sides thereof, it will be seen that the same may be opened from either side and also closed from either side.

20 From the foregoing description of the construction of my improved device, the operation thereof will be readily understood and it will be seen that I have provided a gate which is simple in construction, inexpensive to manufacture and one which will be very efficient and useful in operation.

While I have particularly described the elements best adapted to perform the functions set forth, it is obvious that various changes in form, proportion and in the minor details of construction may be resorted to without departing from the spirit or sacrificing any of the principles of the invention.

35 Having thus described this invention, what I claim is:—

1. The combination with a hinge post; of a gate, upper and lower pintles carried on the vertical bar at the hinging end of said gate and extending in vertical alinement therewith, means engaging said upper pintle to loosely hinge the same to said hinging post, a stationary plate mounted at the base of said hinge post and provided with an 40 arcuate groove in the upper face thereof, the bottom of said groove being undulated and adapted to receive the lower pintle thereon,

and means for manually moving said lower pintle in the groove from both sides of the hinge post.

2. The combination with a hinge post, an outer gate post spaced therefrom, and a pair of stop posts spaced on opposite sides of said hinge post and in alinement with the latter; of a gate, upper and lower pintles carried on the vertical bar at the hinging end of said gate and extending in vertical alinement therewith, means engaging said upper pintle to loosely hinge the same to said hinge post, a stationary plate mounted 50 at the base of said hinge post and provided with an arcuate groove in the upper face thereof, said groove having an undulated bottom surface receiving the lower pintle thereon, flexible connecting means engaged with said lower pintle and loosely engaged with said stop posts, and means in engagement with the ends of said flexible connecting means to move said lower pintle in the aforesaid groove, whereby said gate will be 55 swung to various positions.

3. The combination with a hinge post; of a gate, upper and lower pintles carried on the vertical bar at the hinging end of said gate and extending in vertical alinement 75 therewith, an eye secured to the upper end of the hinge post and loosely receiving the upper pintle therein, a stationary plate mounted at the base of said hinge post and provided with an arcuate groove in the upper face thereof receiving the lower pintle therein, the bottom of said groove being undulated and terminating at the ends in cavities, and means in engagement with said lower pintle for manually moving the same 80 in said groove, whereby to swing said gate to its various positions.

In testimony whereof I hereunto affix my signature in the presence of two witnesses.

SAM A. CRAIG.
